UNITED STATES PATENT OFFICE.

FREDERICK J. MOORE, OF BROOKLYN, NEW YORK, ASSIGNOR OF ONE-HALF TO PHILIP HOWARD REID, OF SHEEPSHEAD BAY, NEW YORK, NO. 1,072,635.

AUTOMOBILE HEATING DEVICE.

1,072,635.

Specification of Letters Patent. Patented Sept. 9, 1913.

Application filed March 20, 1913. Serial No. 755,731.

To all whom it may concern:

Be it known that I, FREDERICK J. MOORE, a citizen of the United States, residing at Brooklyn, in the county of Kings and State 5 of New York, have invented certain new and useful Improvements in Automobile Heating Devices; and I do hereby declare the following to be a full, clear, and exact description of the invention, such as will 10 enable others skilled in the art to which it appertains to make and use the same.

My invention relates to automobile heating devices adapted to divert the lighter and cleaner exhaust gases from internal combustion engines to suitably constructed radiators.

Referring to the drawings wherein the same figures of reference indicate like parts throughout the several views: Figure 1 represents a broken side elevation of the device, and broken view of the exhaust pipe; Fig. 2 is an end elevation of the device looking in the direction of arrow *a* with the head of the drum removed; and Fig. 3 is a broken 25 view partly in section of the drum, plan view of valve, and cross sectional view of the sleeve portion of the rotatable blades, and supporting shaft therefor.

1 is a metal shell or body having the removable heads 2 and 3. Integral with the heads are the interiorly threaded nipples 4 and 5 adapted to be attached to the exhaust pipe 6. The shell is set into the exhaust pipe at any convenient place between the 35 engine and muffler (not shown), the arrow *a* indicating the direction of the exhaust gas from the engine, and arrow *c* to the muffler. The radiator pipe 7 is adapted to be connected with a pipe (not shown) leading to 40 a radiator (not shown) located at any convenient place in an automobile. The gas entering port (not shown) in the nipple 4 and the gas discharging port 8, Fig. 2, in the nipple 5, are located near the bottom of 45 the shell, so that the heavier gases will readily pass through the shell to the muffler, while the lighter and more volatile gases will pass into the radiator. These ports are also located at one side of the center of the 50 shell and in line with each other to not only enable the heavier gases to escape freely, but also to permit the incoming gas to rotate the blades 9 by impinging against one of said blades at one side of its axis of rota-

tion. These blades radiate from the central 55 sleeve 10, which sleeve is journaled on the rod 11 extending transversely through the shell and is secured thereto by the nuts 12. Integral with this sleeve is the valve disk 13 rotatably situated at the inner end of 60 that portion of the pipe 7 projecting into the shell.

14 is a port in the valve disk adapted to register with the open mouth of the pipe 7. 15 is a damper valve in this pipe whose rod 16 is journaled in the walls or sides of the pipe. The outer portion of the rod 16 is bent at right angles and carries at its free end the weight 17 by which this damper valve is kept normally closed, Fig. 2, or the 70 same can be held open, as at Fig. 1, by means of the wire 18, Fig. 2, leading to some place within the automobile and convenient to its occupants. The blades are so placed with respect to the incoming gas that they 75 will rotate continuously, but the port 14 of the valve disk 13 will only register with the pipe 7 at each revolution or rotation of the valve. The advantage of this single valve port is that said port will only register periodically with the pipe, and the time of registering will be so short that none but the lighter and more volatile gases will have an 80 opportunity to pass through this port, while the heavier gases will more readily follow 85 along the line of least resistance into the muffler. It will readily be seen that the shell or body and its internal mechanism will not materially interfere with the back pressure.

90 Minor changes could be made in the construction of the device without departing from the spirit of my invention. While I show the blades, sleeve and valve of one piece, the valve could be made attachable to the sleeve, but for lasting quality and cheapness of construction, the integral form is preferable. While I show the heads 2 and 3 as attached to the ends of the shell, one could be integral with the shell, but the other should be attachable in order that the valve mechanism can first be inserted. While I show the shell of cylindrical form as being most conveniently constructed by simply cutting off a section of wrought iron 100 pipe, it could be made of any desired form best suited to hold the required valve mechanism.

Having thus described my invention, what I claim is:

1. A device of the character described, comprising a shell having inlet and outlet ports located at one side of its axis and adapted to register with the exhaust pipe of an internal combustion engine, rotatable blades located within the shell and in line with the ports thereof, a radiator pipe projecting into the shell, and a valve carried by the blades having a port adapted to register with the mouth of the radiator pipe at each rotation of the blades.
2. A device of the character described, comprising a shell having closed ends with a gas inlet port in one of said ends and a gas outlet port in the opposite end, said ports located at one side of the axis of the shell and adapted to register with the exhaust pipe of an internal combustion engine, rotatable blades located within the shell and in line with the ports in the ends thereof, a radiator pipe projecting into the shell, and a valve carried by the blades and

having a port adapted to register with the mouth of said pipe at each rotation of the blades.

3. A device of the character described, comprising a shell having closed ends with ports therein adapted to register with the exhaust pipe of an internal combustion engine and located at one side of the axis of the shell, a radiator pipe projecting into the shell, a sleeve, a transversely located shaft on which the sleeve is journaled, blades radiating from the sleeve and integral therewith, and in line with the ports in the ends of the shell, and a valve disk integral with the sleeve having a port adapted to register with the mouth of the radiator pipe at each rotation of the blades.

In testimony whereof I affix my signature in presence of two witnesses.

FREDERICK J. MOORE.
